UNITED STATES PATENT OFFICE.

EDWARD G. FELTHOUSEN, OF BUFFALO, NEW YORK.

GAGE-COCK.

SPECIFICATION forming part of Letters Patent No. 224,330, dated February 10, 1880.

Application filed December 29, 1879.

To all whom it may concern:

Be it known that I, EDWARD G. FELTHOUSEN, of Buffalo, in the county of Erie and State of New York, have invented certain new and useful Improvements on a Gage-Cock; and I do hereby declare that the following description of my said invention, taken in connection with the accompanying drawing, forms a full, clear, and exact specification, which will enable others skilled in the art to which it appertains to make and use the same.

This invention has general reference to gage-cocks for steam-generators; and it consists in the peculiar combination of parts and details of construction, as hereinafter first fully set forth and described, and then pointed out in the claim.

The object of my said invention is the production of a gage-cock having a packing to operate in conjunction with a seat to close the vent-opening, said packing being so arranged as to be readily adjusted to compensate for wear.

To this end I construct my gage-cock as shown in the drawing already referred to, in which the figure is a longitudinal sectional elevation, and in which, furthermore, the letter A designates a valve-body consisting of the tapering or otherwise constructed shank B, having a wrench-section, C, by means of which it is screwed into the boiler-plate, and on its forward end a valve-seat, D, the entire body being centrally perforated with a vent-passage, E, for the escape of water or steam.

To the body A is pivoted a gravity-lever, F, by means of a pin, G, said lever having centrally an aperture, H, running longitudinally throughout its entire length and screw-threaded to receive an externally screw-threaded plug, I. This screw-plug I prefer to make of brass, or any other metal uninfluenced by moisture, so as to prevent its being locked in the central aperture, H.

Within the aperture H, I place a packing-plug,

J, consisting, by preference, of either Jenkin's or Johnson's packing, but which may also be made of brass, composition metal, rubber, wood, or, in fact, of any material or metal now used for a like or similar purpose. This packing-block I prefer to make almost as long as the aperture H, (less the length of the screw-plug I,) which will allow the gage-cocks being used for almost an indefinite length of time before renewal will be required, and having placed it into said central aperture I screw the screw-plug I against said packing, which will have the effect of pushing said packing against the seat D, and thereby make a tight joint.

It is now perfectly evident that when leaky nothing remains to be done but to slightly turn the screw-plug I to push the packing-plug J out against the seat D, which action can be repeated as long as a piece of the packing-plug is left.

In some cases it may be necessary to remove the packing-plug to square its face for making a tight joint; but such will be but seldom required, and when necessary can be accomplished in a few moments' time.

Having thus fully described my invention, I claim as new and desire to secure to me by Letters Patent of the United States—

The gage-cock herein described, consisting of the body A, pivoted gravity-lever F, having a central longitudinal screw-threaded aperture, H, throughout its length, the packing-plug J, loosely inserted therein, and the screw-plug I, operating within said passage H, all constructed substantially as set forth.

In testimony that I claim the foregoing as my invention I have hereto set my hand and affixed my seal in the presence of two subscribing witnesses.

EDWARD G. FELTHOUSEN. [L. S.]
